SONIC GENERATOR FOR THE AGITATION OF FLUIDS

Arthur A. Fowle, Waltham, Mass., assignor to Ultrasonic Corporation, Cambridge, Mass., a corporation of Massachusetts

Application May 5, 1951, Serial No. 224,694

8 Claims. (Cl. 259—1)

My invention relates to devices for generating sound waves in bulk liquids.

It has been observed by others that sound waves acting upon various liquids exhibit phenomena which may be applied to achieve many valuable results. For example, sonic energy is useful for pasteurizing milk, for accelerating the chemical processes involved in the ageing of spirits, for making emulsions, and for many other purposes. These phenomena have been observed largely upon a laboratory scale in the past, generally in conjunction with electronically generated sonic energy involving the use of piezo-electric crystals or magnetostriction rods. However, the power losses and large cost of equipment involved in the generation of sound waves by such means are so large as to render it unfeasible from the economic standpoint to utilize them on a commercial scale.

The primary object of my invention is to reduce the cost and improve the efficiency in the operation of generating sound waves in bulk liquids.

An important feature of the invention resides in the combination of a valve supported on a flexible diaphragm and arranged to operate as a water hammer to set up pressure waves in a liquid caused to travel between the valve and its seat.

Another feature of the invention resides in the combination of a duplex conduit having a water hammer at one end and a treating tank at the other, the two parts of the conduit being separated by a plug of solid material having an acoustic impedance comparable to that of the liquids involved. By means of this arrangement one liquid may be employed to operate the water hammer through a closed system including a pump and the water hammer, while the other portion of the conduit may be employed for the passage of the liquid to be treated.

These and other objects and features of my invention will more readily be understood and appreciated from the following detailed description of a preferred embodiment thereof selected for purposes of illustration and shown in the accompanying drawings in which:

Fig. 1 is a diagrammatic view of an entire sonic treating system constructed in accordance with the invention;

Fig. 2 is a plan view of the water hammer;

Fig. 3 is a view in cross section along the line 3—3 of Fig. 2, and

Fig. 4 is a view in cross section through the valve and its seat.

With reference first to Fig. 1, it will be seen that there is provided a heavy hollow housing 10 having a central hollow boss 12 forming a chamber 14 into the outer end of which a pipe 16 is inserted. Within the chamber 14 there extends a valve stem 22 terminated by a valve 30 and supported by and extending through the center of a resilient steel diaphragm 20 held at its periphery by the housing 10. Across the rear of the housing 10 there is secured a heavy strap 18 provided with a threaded central aperture for a rod 26 held in fixed position by a lock nut 28 and carrying at its inner end a rubber stop or bumper 24 disposed in axial alignment with the end of the valve stem 22. A conduit 32 connects the pipe 16 to a high pressure tank served by a variable drive pump connected to a low pressure tank which in turn is connected to the interior of the housing 10 by a drain conduit 36. A pressure gauge 34 is inserted in the line from the pump to indicate the pressure being maintained in the system.

When the pump is operated liquid under pressure flows from the high pressure tank through the conduit 32 and into the pipe 16. It surges against the valve head 30 and

causes the valve stem and valve head to reciprocate, thus alternately increasing and decreasing the space between the valve head 30 and its seat in the boss 12. The valve stem 22 is so adjusted with respect to the diaphragm 20

- 5 that the valve head 30 does not actually touch the boss 12 at any time during its cycle of movement. The rod 26 is adjusted axially in the strap 18 so that the bumper 24 will be struck by the end of the valve stem 22 when the valve 30 is not quite in contact with the boss 12.
- 10 The surge of pressurized liquid first causes a closing movement of the valve 30 and the resiliency of the diaphragm 20 then causes reverse movement of the valve to open the passage. While a diaphragm is an efficient form of resilient member for the purpose, a heavy compression
- 15 spring or other suitable spring may be employed in place of the diaphragm. In consequence of the movement of the valve 30 and the alternate decrease and increase in the flow of fluid through the valve, there is generated in the pipe 16 pressure waves which travel through the liquid at a frequency within the sonic range. The frequency is the natural frequency of the system.

Liquid which has passed through the valve 30 and into the interior of the housing 10 drains through the conduit 36 into the low pressure tank from which it is again pumped into the high pressure tank. I provide a relief valve 40 in a by-pass conduit 38 connecting the high and low pressure tanks. The pressure relief valve 40 may be set to control the flow rate of the liquid. Thus the speed of the pump may be varied to vary the pressure

20 30 in the system while the relief valve 40 may be adjusted to attain a desired flow rate.

The operation of the water hammer is based upon the principle of a "self-growing" water hammer wherein the flow through the valve is reduced when the pressure upon

35 the valve rises and wherein the flow through the valve is increased when the pressure upon the valve falls. In constructing a water hammer sound wave generator of the type disclosed herein, it should be borne in mind that under one set of conditions the operation is stable; that

40 is to say, the fluid is pumped through the circuit in a steady flow, but under another set of conditions the valve mechanism is set in self-excited vibration which causes an interruption of the fluid flow at the valve with the consequent generation of pressure pulses proceeding away from the valve. Ordinarily a small pressure pulse generated at the valve end of the pipe will make multiple reflections at both ends of the pipe until it is damped out. However, if the valve is so constructed that it operates in the manner described above, the pressure wave being

50 reflected from the valve is actually increased in amplitude due to the motion of the valve; this amplitude of the pressure wave increases until it is limited by damping or by cavitation. The natural frequency of the sound waves in such a system is that corresponding to the natural vibration frequency of the water column in the pipe,

55 the period being the time the pressure wave requires to traverse the length of the pipe four times. From an inspection of Fig. 1 it will be evident that as pressure is applied upon the valve 30 by the liquid in the pipe 16, the

60 valve moves to the left and thereby decreases the flow, since the valve passage is decreased in volume. Then as the pressure upon the valve 30 is decreased, the valve moves to the right (due to the force of the spring diaphragm 20) and the flow past the valve increases. It should be noted that the chamber into which the fluid flows from the valve is sufficiently large and is also drained adequately so as to permit the diaphragm to oscillate in air undamped by the presence of a significant volume of liquid.

70 In the pipe 16 above the liquid inlet conduit 32 there is disposed a solid plug 42 of a material having an acoustic impedance comparable to that of the liquid employed to operate the water hammer. This liquid may conveniently comprise oil of the type commonly used in hydraulic systems, and the plug 42 may be constituted of rubber or similar material having a compressibility similar to that of the oil.

Above the plug 42 the pipe 16 is provided with an inlet conduit through which the liquid to be treated may be introduced into the system. The end of the pipe 16

75 80 leads into a large surge tank provided with an outlet

so that the liquid undergoing treatment may be passed continuously through the system. A pressure gauge 44 is provided upon the tank so that the pressure of the system may be observed. If the intensity of the waves generated in the water hammer are sufficiently high, cavitation may be experienced. However, pressure may be applied to the surge tank so that the liquid undergoing treatment is subject to a pressure high enough to eliminate cavitation. On the other hand, in certain processes cavitation may prove efficacious in promoting the desired result, in which case the liquid to be treated will be circulated with minimum pressure.

In Figs. 2, 3 and 4 an embodiment of the water hammer is shown in more detail than in Fig. 1. There is provided a stout metal plate 50 into which is threaded the end of a pipe 52, this pipe being similar in function to the pipe 16 shown in Fig. 1. A second flat plate 54 is secured to the plate 50 by a series of bolts 58 and contains a hollow block 56 provided with a passage for a valve stem 70 carrying an integral head 60 disposed opposite a seat formed in the interior of a hollow block 56. Incidentally a portion of the block immediately surrounding the valve seat is provided with a concave annular recess 62 in order to minimize turbulence above the valve.

Welded or otherwise suitably secured to the face of the plate 54 is a cylindrical metal housing 64 which is threaded internally to receive a pair of clamping rings 66 between which is held the margin of a resilient diaphragm 68, of low alloy tool steel or similar tough resilient metal. The ring 66 and the margin of the diaphragm 68 are secured by a circumferential series of bolts 67. A stout strap 72 disposed across the housing 64 and bolted thereto is provided with a threaded aperture at the center to receive a threaded rod 76 carrying on its inner end a rubber bumper 74 and secured in position upon the strap 72 by a lock nut 80. The bumper 74 serves as a damping pad for limiting the travel of the valve; this eliminates mutilation of the valve due to pounding as well as failure of the diaphragm due to overstress.

The rings 66 are held in fixed position by four bolts 82 which pass through lugs 84 bolted to the rear end of the cylindrical housing 64. It will be appreciated that the rings 66 may be adjusted in and out with respect to the housing 64 and thereby vary the clearance of the valve 60 with respect to its seat. In this way the pressure at the valve may be adjusted, the pressure decreasing as the valve clearance is increased.

It will be evident that a water hammer generator of the type herein disclosed will be more effective at relatively low frequencies, say from 100 to 1,000 cycles per second. However, at such frequencies considerable sonic energy may be developed; for example, sound waves in the order of ten kilowatts may easily be obtained.

While the device as shown herein utilizes the back generated pressure waves traveling from the valve 30 through the pipe 16, it is equally possible to couple the diaphragm 20 to a suitable treating or radiating system wherein the diaphragm serves as a source of useful sound waves. Alternatively a drill bit may be mounted upon the diaphragm to form an impact drilling rig.

The nature of the work to be done and the frequency desired for operation will, of course, affect the design adapted for any particular application but it is believed that the foregoing description is adequate to provide those skilled in the art with sufficient information to permit successful commercial embodiments of the invention to be constructed.

Having thus disclosed my invention and described in detail specific embodiments thereof I claim as new and desire to secure by Letters Patent:

1. Sonic treating apparatus comprising an elongated conduit, a plug intermediate the ends of said conduit dividing said conduit into first and second compartments, means for supplying an operative fluid under pressure to the first compartment, means adjacent the first compartment end of said conduit responsive to the operative fluid in said first compartment to produce back pressure sonic waves in said first compartment, and means for supplying a liquid to be treated to the second compartment, said first compartment and said plug providing an acoustical connection for the sonic waves from the sonic wave producing means to said second compartment.

2. Sonic treating apparatus as defined in claim 1, wherein the means for producing back pressure sonic waves comprises a chamber in fluid communication with said first compartment, a valve means mounted in said chamber in the path of fluid leaving said first compartment, resilient means coupled to said valve means to oppose movement of said valve means and a stop operatively associated with said resilient means to prevent closing of said valve means.

3. Sonic treating apparatus comprising an elongated conduit, a solid plug in said conduit dividing said conduit into two compartments, means for introducing a liquid to be treated into one compartment, means for introducing an operative fluid into the other compartment, and means including a resilient diaphragm controlled valve mounted externally of said other compartment restricting the passage of operative fluid out of said other compartment for producing back pressure sonic waves in said other compartment, said plug having an acoustic impedance comparable to the operative fluid, whereby said plug and operative fluid provide a transmitting medium for said pressure waves between said valve and said fluid to be treated.

4. Sonic treating apparatus comprising a conduit, a plug dividing said conduit into two compartments, means for supplying an operative liquid to one of said compartments, means for circulating a liquid to be treated through the other of said compartments, and means adjacent the first-named compartment end of said conduit responsive to the said operative liquid to produce back pressure sonic waves in said first-named compartment, the length of the conduit being such that the liquid filled conduit is resonant at said sonic frequency.

5. Sonic treating apparatus comprising an elongated conduit, a plug dividing said conduit into two compartments, means for introducing a fluid under pressure to one of said compartments, means responsive to said fluid for generating pressure waves at a sonic frequency, and means for circulating a fluid to be treated through the other of said compartments, the combined length of the two compartments being such that the fluid filled conduit is resonant at said frequency.

6. Sonic treating apparatus as defined in claim 5 wherein said plug is made of material having an acoustic impedance comparable to that of the fluid to which the means for producing pressure waves responds.

7. A sonic wave generator comprising walls forming a hollow housing, a hollow member projecting through a wall of said housing, a valve opening formed in said member communicating with said housing, means for supplying an operative fluid under pressure to said member, a valve mounted for axial movement in said member operatively associated with said valve opening movable in response to the flow of operative fluid to restrict said opening from the member to the housing, a resilient diaphragm mounted in said housing and coupled to said valve urging said valve to a non-restricting position after said opening has been partially restricted, a stop member cooperating with said diaphragm for preventing said valve from closing said opening and means for draining fluid from said housing.

8. Sound wave producing means comprising a chamber, an inlet and an outlet for said chamber, a conduit coupled to said inlet adapted to pass fluid to said chamber, a valve operatively associated with said inlet movable in response to fluid flow in said conduit to partially restrict said inlet, a spring loading said valve to a non-restricting position for moving said valve to said non-restricting position upon a reduction of fluid flow in said conduit, means supplying liquid under pressure to said conduit, valve and chamber; the load of said spring, the diameter and length of said conduit, and the mass of said valve being such that upon the application of pressure to said liquid, said valve opens and closes at a frequency equal to the resonant frequency of said conduit.
